UNITED STATES PATENT OFFICE.

GROVER W. BURLISON, OF GRUNDY, VIRGINIA.

RAIL SPREADER.

Application filed November 3, 1921. Serial No. 512,544.

To all whom it may concern:

Be it known that I, GROVER W. BURLISON, a citizen of the United States, residing at Grundy, in the county of Buchanan and State of Virginia, have invented a new and useful Rail Spreader, of which the following is a specification.

This invention aims to provide a simple means whereby the rails of a railway track 10 may be spread apart or drawn together.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described 20 and claimed, it being understood that, within the scope of what is claimed, changes in the precise embodiment of the invention shown can be made without departing from the spirit of the invention.

In the accompanying drawings:—

Figure 1 shows in side elevation, a device constructed in accordance with the invention; Figure 2 is a top plan; Figure 3 is a fragmental longitudinal section showing the 30 main lever and attendant parts in elevation; Figure 4 is a fragmental longitudinal section showing one of the dogs and attendant parts in elevation.

The device forming the subject matter of this application includes a first member 1 made up of parallel bars 3 having seats 4 adapted to receive one rail 5 of a track. The bars 3 are connected by securing elements 6, 7 and 8, such as bolts. Standards 40 9 are held on the bars 3 by the securing element 6. A dog 10 is located between the standards 9 and is pivotally mounted thereon, as indicated at 11. Standards 12 are mounted on the bars 3 and are held thereon by the securing element 8. A dog 14 is located between the standards 12 and is pivotally mounted thereon as indicated at 15.

The device includes a second member 2 made up of parallel bars 16 located between the bars 3 of the first member 1 and slideable longitudinally with respect thereto, the bars 16 having seats 17 adapted to engage one rail 18 of a track. The bars 16 of the 55 second member 2 are supplied with enlon-

gated slots 19 receiving the securing elements 6, 7 and 8 to the end that relative longitudinal movement between the members 1 and 2 may take place. Racks 20 are formed in the upper edges of the bars 16 60 of the second member 2. The dogs 10 and 14 are adapted to cooperate, one at a time, with the racks 20, and have curved surfaces 21. Suppose that the members 1 and 2 are moved outwardly with respect to each other as indicated by the arrows A in Figure 1. Then, the dog 10 prevents the members 1 and 2 from moving inwardly in the direction of the arrows B, the curved surface 21 of the dog 14 engaging the racks 20, and the said 70 dog having no holding effect, but merely sliding over the racks. Suppose that the members 1 and 2 are moved inwardly with respect to each other as indicated by the arrows B in Figure 1. Then, the dog 10 75 is swung over in the direction of the arrow C in Figure 1, until its rounded or curved surface 21 cooperates with the racks 20, the dog 10 then having no holding effect. The dog 14 is swung over in the direction 80 of the arrow D until it is in holding relation to the racks 20, and, then when the members 1 and 2 are moved inwardly, in the direction of the arrows B, the dog 14 prevents the said members from moving 85 outwardly in the direction of the arrows A.

The means for producing relative longitudinal movement between the members 1 and 2 embodies a main lever 22, the lower end of which is located between the bars 90 16 of the member 2 and is mounted to swing on the securing element 7. Pawls 23 and 24 are pivotally mounted at 25 on the main lever 22 and project in opposite direction therefrom. The pawls 23 and 24 95 have openings 26 receiving slidably, releasing members denoted by the numeral 27. The releasing members 27 have projections 50, at their lower ends, adapted to cooperate with the respective pawls 23 and 24. The upper ends of the releasing members 27 are pivoted at 28 to auxiliary levers 29 100 fulcrumed at 30 on the main lever 22. Each auxiliary lever 29 has a keeper 31 in the form of an eye, adapted to coact with a latch 32, such as a hook, pivoted at 33 on the lever 22. Either auxiliary lever 29, together with its releasing member 27 and the corresponding pawl 23 or 24, may be held in operative position, through the in- 110

strumentality of the latch 32, one pawl 24 remaining in operative relation to the racks 20 of the bars 26, and sliding on the corresponding releasing member 27 as the said 5 pawl moves to engage a new hold on the racks 20. Obviously, the pawl 24 is used when the members 1 and 2 are to move apart in the direction of the arrows A, the pawl 28 being used when the members 1 and 2 10 are to be moved inwardly, in the direction of the arrows B.

What is claimed is:—

1. In a device of the class described, first and second members, connected for relative 15 longitudinal sliding movement, the second member having a rack; reversible dogs carried by the first member and adapted to engage the rack; a lever mounted to swing on the first member; pawls carried by the 20 lever and adapted to cooperate one at a time with the rack; and means for holding

either pawl out of engagement with the rack.

2. In a device of the class described, a first member comprising bars; a securing 25 element connecting the bars; a second member comprising bars located between the bars of the first member and having elongated slots receiving the securing element; a lever disposed between the bars of the 30 second member and mounted to swing on the securing element; and a pawl mounted on the lever and coacting with one of the bars of the second member.

In testimony that I claim the foregoing 35 as my own, I have hereunto affixed my signature in the presence of two witnesses.

GROVER W. BURLISON.
